UNITED STATES PATENT OFFICE.

JESSE A. B. SMITH, OF STAMFORD, CONNECTICUT, ASSIGNOR TO UNDERWOOD ELLIOTT FISHER COMPANY, OF NEW YORK, N. Y., A CORPORATION OF DELAWARE.

TYPEWRITING MACHINE.

Application filed January 31, 1927. Serial No. 164,673.

This invention relates to typewriting machines, in which work-sheets arranged side by side may be line-spaced alternately, and more particularly to means for employing an 5 interposed ink-ribbon for manifolding purposes.

Two platens are usually rotatively mounted side by side on a traveling carriage, one for each work-sheet, and each platen is provided with independent line-spacing mechanism. The carriage may be returned to starting position by either line-space lever. According to the present invention, an ink-ribbon is stretched across the two platens, in 15 front thereof, and is wound from a supply-spool into a receiving spool, which is rotated to feed the ribbon to thereby present fresh portions thereof to the printing field. This ribbon is interposed between superposed 20 work-sheets, two or more of which are superposed at each side of the double platen, although in some cases a single platen of double length may be employed. The interposed ribbon or ribbons are mounted on the carriage, while the ordinary vibrating ink-ribbon 25 is mounted on the machine-frame.

This novel ribbon-mechanism is mounted on a displaceable frame carried by the carriage, and is operatively connected by means 30 of a cross-bar to the line-spacing mechanism of both platens. The cross-bar is swung by operation of either line-spacing mechanism, and is provided at the ends thereof with operating pawls which engage ratchet-wheels 35 carried by the ribbon-spoils. The ribbon may thus be fed or wound regardless of which one of the two platens is operated, and the feeding direction thereof may be changed at will by means of a ribbon-reversing mechanism, which is effective to simultaneously render effective the pawls associated with one 40 of the spools while rendering ineffective the pawls associated with the other spool. The means for operating these pawls is also effective to throw on and off retaining pawls which prevent back-rotation of the ratchet-wheels.

This machinery may be used to advantage 45 for combined billing and ledger-posting, in which it is customary to make a record-sheet of both the bills and the ledger-entries. Heretofore much trouble has been experienced in handling a carbon-sheet which had to be assembled with the bill-sheet and the ledger- 50 sheet prior to inserting them in the machine.

By means of this invention the operation is facilitated since the record-sheet is left permanently in the machine and the ribbon takes the place of the carbons. The record-sheet is held in place by means of pressure-rolls running on the platen at the top thereof, and, in order to insert the bill-sheet and the ledger-sheet, it is only necessary to release the regular feed-rolls under the machine and to position the sheets to the printing line. Then the 60 feed-rolls are made operative, and the same entry may be made on both sheets by presenting either of the two platens to the printing point.

In order to facilitate the insertion of the 70 record-sheets around the platens, the ribbon-frame and the pressure-rolls are swung together to inoperative position, thereby clearing the leading edges of the record-sheets, which may then be positioned by rotating the platens. The ribbon is preferably supported at a point between the two platens by means of a bracket carried by the ribbon-frame and swingable therewith. 75

Other features and advantages will here- 80 inafter appear.

In the accompanying drawings.

Figure 1 is a front view in elevation of an Underwood twin-platen machine having the 85 novel ribbon mechanism applied thereto.

Figure 2 is an end view showing the ribbon-feeding mechanism connected to the line-feeding slide of an Underwood machine.

Figure 3 is a diagrammatic view showing the ribbon-feeding mechanism in inoperative 90 position.

Figure 4 is a front cross-sectional view showing the left-hand end of the ribbon-operating mechanism.

Figure 5 is a plan view of the platen-frame 95 with the ribbon-spoils removed, and shows the independent line-spacing mechanism for each platen.

Figure 6 is a diagrammatic view showing the ribbon-feeding mechanism in operative 100 position.

Figure 7 is a diagrammatic view showing the ribbon-frame swung to ineffective position to facilitate the insertion of the record-sheets.

Figure 8 is a perspective view showing the central ribbon-supporting bracket and the pressure-rolls for holding the record-sheets in registration around the platens.

A pair of platens 10 and 11 are rotatively 110

mounted on shafts 12 and 13, and each is independently operable by means of finger-pieces 14 and 15, and by line-spacing mechanisms operatively connected to ratchet-wheels 16 and 17 carried by the shafts 12 and 13. The two shafts are journaled in end-plates 18 and 19 which, together with a cross-plate 20, form the platen-frame of the machine, which is shiftable on a traveling carriage, not shown.

The line-spacing mechanism is of the well-known Underwood standard type, in which either of two slides 21 and 22 may be reciprocated by their associated line-spacing handles 23 and 24. Each slide carries a pawl 25 which is normally held out of engagement with its associated ratchet-wheel by means of a pin 26. Upon operation of the line-spacing handle, however, the slide 21 is moved rearwardly against the tension of a returning spring 27, and the pawl is thrown into engagement with the teeth of the ratchet by means of a spring 28, thereby rotating the platen and line-spacing the work-sheet there-around.

A ribbon 29 is unwound from a supply-spool 30 and is led downwardly and through a slot 31, the ribbon is crossed at right angles and is stretched across the two platens 30 covering the printing line thereof and through a slot 32, is again crossed at right angles and is led upwardly into a receiving-spool 33. The spools are mounted on end-frames 34 and 35 which are fast to a cross-shaft 36 rotatably mounted on the end-plates of the platen-frame. The frames 34 and 35 extend forwardly and are bent at 37 to form ears in which the slots 31 and 32 are perforated. The upper ends of the frames are bent to provide outer bearings 38 and 39 for shafts 40 and 41 carrying respectively the supply and receiving spools. Each shaft carries a ratchet 42 fast thereto and each ratchet is arranged to be engaged by one of two pawls 43 carried by one of two cam-plates 44 with which the pawls are operatively connected by means of pins 45. The cam-plates are secured to a cross-tube 46 journaled in the end-frames 34 and 35, and are both provided with downwardly-extending fingers 47 designed to engage pins 48 carried by the slides 21 and 22. Figure 2 shows the inoperative position on the slide 21, in which position the cam-plate is held in the position shown by means of a spring 49 which is stretched between a spring-stud 50 and a pin 51 carried by the cam-plate. The latter is arrested by a pin 52 carried by the end-frames. The pawl 43 is held in engagement with the ratchet 42 by a spring 53, and each time either of the two operating slides is moved rearwardly by actuation of its corresponding line-space lever, the pin 48 associated therewith engages the finger 47, thereby rocking the tube 46 and elevating the pawl 43, which be-

ing connected with the ratchet-wheel will advance the same and a small portion of the ribbon will be wound on the receiving spool. During the return movement of the slide the ribbon is prevented from unwinding by a retaining pawl 54, which is pivotally mounted on a stud 55, and is held in engagement with the rod by means of a spring 56 stretched between the stud 50 and a pin 57, the latter being fast to an extension 58 of the pawl 54. The operative position of the slide and other mechanism associated therewith is shown in Figure 6.

In order that either of the two spools may be used as a receiving spool for the ribbon so that the same may be fed in either direction, there is provided a manual ribbon-controlling mechanism which automatically reverses the feed of the operating and retaining pawls, so that the pawls at one end may be rendered effective while the pawls at the other end are rendered ineffective. This mechanism may include a pair of cam-plates 59 and 60, which are fast at either end of a cross-shaft 61 protruding at the ends of the tube 46. These cam-plates are provided with finger-pieces 62 and 63, and are so contoured that when any one of the finger-pieces is pressed downwardly the pawls operating on the left-hand ribbon-spool are rendered inoperative as shown in Figure 3, while the pawls actuating on the right-hand spool are thrown into engagement with the ratchet as shown in dotted lines in Figure 2. When the shaft 61 is swung to move the finger-pieces upwardly the effectiveness of the pawls is reversed, so that the left-hand spool will be made operative while the right-hand spool is made inoperative. The cam-plates are provided with retaining notches 64 and 65 which engage the pins 57 carried by the pawls 54. By referring to Figure 3 it will be noticed that upon swinging the pawl 54 to an inoperative position the back thereof will strike the pawl 43, thereby swinging it also to inoperative position.

The spools 30 and 33 are mounted on the shaft 40, and may be taken out to replace the ribbon when desired by unscrewing finger-pieces 67 on the inner ends of the shafts which normally hold the spools in engagement with pins 68 carried by a flange 69 forming an integral part of the shafts. Each pin 68 enters a hole in the hub of its associated spool, thereby driving the same with the shaft. In order that the supply-spool may be prevented from unwinding ahead of the receiving-spool, the shafts 40 and 41 are provided with retaining springs 70 which serve as a brake for the spool from which the ribbon is unwound.

The insertion of the record-sheets around the platens is facilitated by swinging the ribbon-frame on the shafts 36 to a position such as is indicated in Figure 7. The frame is swung by operating finger-pieces 71, which may form an integral part of the

frames 34 and 35, held in either operative or inoperative position by means of a retaining pawl 72. The latter is pivotally mounted on a stud 73 carried by the end-plate 18 and is held in engagement with either of two notches 74 in the frame 34 by a spring 75. Only one of these retaining pawls is required, since both plates 18 and 19 are mounted on the shaft 36, thereby forming a rigid structure.

10 The record-sheets 76 are held in place around the platens by pressure-rolls 77 carried by spring-leaves 78, which are bent to conform with the periphery of the platens and are in turn carried by rigid supporting frames 79 which are secured to the shaft 36 by means of screws 80. The desired pressure on the record-sheets is obtained by swinging the frames 79 around the shaft 36 prior to tightening the screws 80. When the ribbon-carrying frame is swung to inoperative position the feed-rolls are automatically released or swung upwardly, as shown in Figure 7, thus further facilitating the insertion of the record-sheets around the platens.

25 The ribbon is supported at a point between the two platens by a bracket 81 carried by the shaft 36 to which it is secured by means of a pin 82. The bracket 81 is bent to clear the platens, and extends forwardly and downwardly from the shaft 36, being provided at the end thereof with openings 83, through which the ribbon is threaded to prevent the same from sagging and interfering with the proper line-feeding of the work-sheets.

35 The original statement and bill sheets indicated by the numeral 84 are preferably front inserted by releasing feed-rolls 85, and with the aid of a front inserting device, not shown, but well known in the art, the sheets are typed by means of the regular type-bars 86 and the usual vibrating ribbon 87, which is carried by a vibrating frame 88 slidably mounted on a type-guide 89.

45 Variations may be resorted to within the scope of the invention, and portions of the improvements may be used without others.

Having thus described my invention, I claim:

1. In a typewriting machine, having a 50 twin-platen and a line-spacing mechanism for each platen mounted in a traveling carriage, a ribbon in front of both platens covering the printing line thereof, and means for feeding said ribbon upon operation of either line-spacing mechanism.

2. In a typewriting machine, the combination of a pair of platens journaled in a traveling carriage, a line-spacing mechanism for each platen, a ribbon covering the printing line of both platens, and means controlled by either of the line-spacing mechanisms for selectively feeding the ribbon in either direction upon operation of either line-spacing mechanism.

3. In a typewriting machine, the combina-

tion of a pair of platens rotatively mounted side by side, a carriage for said platens, a ribbon-frame for holding a ribbon in front of said platens at the printing line, pressure-rolls carried by said ribbon-frame for holding record-sheets around the platens, means for concomitantly swinging the ribbon and the pressure-rolls to inoperative position to facilitate insertion of the record-sheets, and a bracket for supporting the ribbon at a point 75 between the two platens, said bracket being carried by the ribbon-frame and swinging therewith to an effective position.

4. In a typewriting machine having a twin-platen journaled in a traveling carriage and a line-spacing mechanism for each platen, a ribbon in front of both platens and in close proximity thereto, and means for feeding the ribbon during line-spacing movement of either platen, said means being effective to 85 feed the ribbon in the same direction upon operation of either platen.

5. In a typewriting machine, the combination of a pair of platens journaled in a traveling carriage and each having independently 90 operated line-spacing mechanisms, a ribbon covering the printing line of both platens, a pair of spools for said ribbon, and means for feeding the ribbon from one spool to the other upon operation of either line-spacing mechanism.

6. In a typewriting machine, having a twin-platen and a line-spacing mechanism for each platen, each of said line-spacing mechanisms including a reciprocating slide and a 100 line-spacing handle associated therewith, a ribbon covering the printing line of both platens, and means for feeding said ribbon, said means including a pair of spools, means associated with the line-spacing slides for 105 winding the ribbon from one spool to the other, and means for selectively controlling the receiving spool to thereby feed the ribbon in either direction, said last two mentioned means including a cross-shaft rockable upon 110 operation of either line-spacing slide, a pair of feeding pawls carried by said cross-shaft, a ratchet for each ribbon-spool, each ratchet being engageable by its associated pawl, a retaining pawl for each ratchet to prevent back 115 rotation thereof, and manually-operable mechanism for engaging the operating and retaining pawls associated with one of the ratchets while concomitantly disengaging the pawls associated with the other ratchet.

7. In a typewriting machine, having a twin-platen, a ribbon stretched in front of both platens and in close proximity thereto, means for feeding the ribbon in either direction, means for moving the ribbon, away from the platens to permit insertion of work-sheets between the ribbon and the platens, and means for supporting the ribbon at a point between the two platens to prevent sagging thereof.

8. In a ribbon-feeding mechanism for a 130

- typewriting machine having a pair of side-by-side platens journaled in a traveling carriage and a line-spacing mechanism for each platen, a pair of ribbon-spools overlying said platens, means for guiding a ribbon along the printing line of the platens, said ribbon being unwound from one of the spools and wound onto the other spool, and means for selectively rotating at will either spool upon operation of either line-spacing mechanism, to thereby feed the ribbon in a predetermined direction regardless of which line-spacing mechanism is operated.
9. In a ribbon-feeding mechanism for a typewriting machine having a pair of side-by-side platens and a line-spacing mechanism for each platen, a pair of ribbon-spools overlying said platens, means for guiding a ribbon along the printing line of the platens, said ribbon being unwound from one of the spools and wound into the other spool, and means for selectively rotating at will either spool upon operation of either line-spacing mechanism, to thereby feed the ribbon in a predetermined direction regardless of which line-spacing mechanism is operated, said last-mentioned means including a ratchet-wheel rotatable with each ribbon-spool, a driving pawl for each ratchet-wheel, means for selectively connecting either pawl with its associated ratchet-wheel, means for operatively connecting the driving pawls with both line-spacing mechanisms, whereby either pawl may be reciprocated upon operation of either line-spacing mechanism, and a pair of retaining pawls, one retaining pawl associated with each ratchet-wheel, for selectively preventing back-rotation of either ratchet-wheel.
- 40 10. In a typewriting machine having a twin-platen journaled in a traveling carriage and independent line-spacing mechanism for each platen, means for conducting a ribbon along the printing line of both platens, and means associated with both line-spacing mechanisms for feeding the ribbon in a selectively predetermined direction upon operation of either line-spacing mechanism.
11. In a typewriting machine having a twin-platen and independent line-spacing mechanism for each platen, means for conducting a ribbon along the printing line of both platens, and means associated with both line-spacing mechanisms for feeding the ribbon in a selectively predetermined direction upon operation of either line-spacing mechanism, said last-mentioned means including a pair of ribbon-spools overlying the platens, means for conducting the ribbon from one spool, along the printing line, onto the other spool, and means including a shaft overlying the platens and having driving connections with both line-spacing mechanisms for operatively connecting either line-spacing mechanism with either ribbon-spool.

12. In a typewriting machine having a twin-platen and independent line-spacing mechanism for each platen, means for conducting a ribbon along the printing line of both platens, a pair of ribbon-spools rotatably mounted to feed the ribbon from one to the other, and means actuated upon operation of either of said line-spacing mechanisms for positively rotating either one of said spools to wind the ribbon thereon.

13. In a typewriting machine having a twin-platen and independent line-spacing mechanism for each platen, means for conducting a ribbon along the printing line of both platens, a pair of ribbon-spools rotatably mounted to feed the ribbon from one to the other, and means associated with each of said line-spacing mechanism and actuated upon operation of either mechanism for positively rotating either one of said spools selectively to wind the ribbon thereon.

14. In a typewriting machine having a twin-platen and independent line-spacing mechanism for each platen, means for conducting a ribbon along the printing line of both platens, a pair of ribbon-spools rotatably mounted to feed the ribbon from one to the other, a shaft, a driving connection between each of said line-space mechanisms and said shaft, whereby operation of either of said mechanisms will cause actuation of the shaft, and spool-driving mechanism operated by said shaft and connectible to either of said spools to positively rotate the same to wind the ribbon thereon.

15. In a typewriting machine having a twin-platen and independent line-spacing mechanism for each platen, means for conducting a ribbon along the printing line of both platens, a pair of ribbon-spools rotatably mounted to feed the ribbon from one to the other, a shaft, a driving connection between each of said line-space mechanisms and said shaft, whereby operation of either of said mechanisms will cause actuation of the shaft, spool-driving mechanism associated with each spool and operated by said shaft, and means for simultaneously rendering one of said spool-driving mechanisms operative and the other inoperative, selectively, to determine the direction of travel of said ribbon.

16. In a typewriting machine having a traveling carriage, the combination with a pair of platens journaled in said carriage, and line-spacing mechanism for each platen, of a pair of ribbon-spools having a ribbon running from one to the other, means for guiding said ribbon in front of the printing line, driving means for said spools actuated upon operation of either of said line-spacing mechanisms, and means for connecting either spool to said driving means to wind the ribbon thereon.

17. In a typewriting machine having a traveling carriage, a twin-platen journaled

therein and independent line-spacing mechanisms for the platen-sections, the combination of a pair of spools, means for guiding a ribbon from spool to spool and in a horizontal stretch in front of the printing line, means for driving either spool to wind the ribbon thereon upon operation of either line-spacing mechanism, including a one-way driven mechanism independently connectible to both line-spacing mechanisms to be driven thereby, and disengageable connections between said driven mechanism and said ribbon-spools, and a frame for supporting said spools and ribbon-guides and all the spool-driving means, whereby the same may be assembled and installed as a unit upon a typewriting machine.

18. In a typewriting machine having a traveling carriage, a twin-platen journaled therein and independent line-spacing mechanisms for the platen-sections, the combination of a pair of spools, means for guiding a ribbon from spool to spool and in a horizontal stretch in front of the printing line, means for driving either spool to wind the ribbon thereon upon the operation of either line-spacing mechanism, means including a one-way driven mechanism independently connectible to both line-spacing mechanisms to be driven thereby, and disengageable connections between said driven mechanism and said ribbon-spools, and a frame for supporting said spools and ribbon-guides and all the spool-driving means, whereby the same may be assembled and installed as a unit upon a typewriting machine, said frame being pivotally mounted upon said carriage to enable it to

be swung to remove said horizontal stretch of the ribbon from the printing line.

19. In a typewriting machine, the combination of a pair of platens rotatively mounted side by side, a carriage for said platens, a ribbon-frame for holding a ribbon in front of said platens at the printing line, means for swinging the ribbon to inoperative position to facilitate the insertion of record-sheets, and a bracket for supporting the ribbon at a point between the two platens, said bracket being carried by the ribbon-frame and swinging therewith.

20. In a typewriting machine having a traveling carriage, the combination with a twin-platen journaled in said carriage and independent line-spacing mechanisms for said platens, of an auxiliary ribbon, means for guiding said ribbon to and across the printing line of both platens, and means for feeding said ribbon in either direction at will, said feeding means including a pair of rotatable spools upon which said ribbon is wound, ratchet-wheels fast upon the spool-shafts, pawls cooperating with said wheels to drive the same, each pawl having an extension projecting into the path of a moving element of one of said line-spacing mechanisms to be actuated thereby to impart oscillatory motion to its associated pawl, a connection between said pawls to transmit motion from one pawl to the other, means for effecting operative engagement of said pawls with said ratchet-wheels, and means for selectively disengaging one of said pawls from its ratchet-wheel to determine the direction of feed of said ribbon.

JESSE A. B. SMITH.
